UNITED STATES PATENT OFFICE.

JOSEPH MATZ, OF BICKNELL, INDIANA, ASSIGNOR OF TWO-THIRDS OF HIS
RIGHT TO J. W. TRUEBLOOD AND JOHN B. WELLS, OF SAME PLACE.

ADJUSTABLE STOVE-LEG.

SPECIFICATION forming part of Letters Patent No. 226,530, dated April 13, 1880.

Application filed February 9, 1880.

To all whom it may concern:

Be it known that I, JOSEPH MATZ, of Bicknell, in the county of Knox, and in the State of Indiana, have invented certain new and useful Improvements in Adjustable Stove-Legs; and I do hereby declare that the following is a full, clear, and exact description thereof, reference being had to the accompanying drawings, and to the letters of reference marked thereon, making a part of this specification.

The nature of my invention consists in the construction and arrangement of an extensible stove-leg, as will be hereinafter more fully set forth.

15 In order to enable others skilled in the art to which my invention appertains to make and use the same, I will now proceed to describe its construction and operation, referring to the annexed drawings, in which—

20 Figure 1 is a perspective view of my stove-leg. Fig. 2 is an enlarged longitudinal section of the same; and Fig. 3 is a cross-section thereof on the line x x , Fig. 2, still further enlarged.

25 My stove-leg is made in two parts, the lower part, A, being the foot, and B the box or upper part.

The upper portion of the foot A fits in the box B, and is provided with a longitudinal

slot, a , through which a bolt, C, passes, said 30 bolt being passed from the front through a hole in the box B. On the bolt C is placed a tapering or conical washer, D, the base of which fits in the foot, as shown, and a nut, b, is then screwed on the end of the bolt, so as 35 to firmly hold the two parts of the leg together.

By this construction the leg can be extended or contracted, as required, to any necessary size.

I am aware that a stove-leg made in two 40 parts and capable of extension and contraction is not new, and I do not claim such, broadly, as my invention.

Having thus fully described my invention, what I claim as new, and desire to secure by 45 Letters Patent, is—

The combination of the box B, foot A, having slot a , bolt C, washer D, and nut b, substantially as and for the purposes herein set forth.

50 In testimony that I claim the foregoing I have hereunto set my hand this 26th day of January, 1880.

JOSEPH MATZ.
